LOADER FOR REVOLVERS

Filed Sept. 27, 1946

UNITED STATES PATENT OFFICE

2,470,182

LOADER FOR REVOLVERS

Ernest L. Peck, Erie, Pa.

Application September 27, 1946, Serial No. 699,602

2 Claims. (Cl. 42—89)

1

My invention relates to a device for charging or loading a revolver or the like.

An important object of my invention is to provide a charger or loader which will particularly facilitate the loading of revolvers, but which may be used to load other suitable pistols or rifles.

A further object is to provide a revolver loader which is compact, and which may be conveniently carried in the pocket of the user.

A still further object of the invention is to provide a revolver loader which is simple and sturdy in construction and convenient to use for rapidly loading a revolver.

Other objects and advantages of the invention will be apparent during the course of the following description.

In the accompanying drawings, forming a part of this application, and in which like numerals are employed to designate like parts throughout the same,

Figure 1 is a central vertical section through the revolver loader embodying my invention parts in elevation, and showing the same associated with the cylinder of a revolver,

Figure 2 is a front elevation of the same, parts broken away,

Figure 3 is a horizontal section taken on line 3—3 of Figure 1, parts omitted,

Figure 4 is a perspective view of the magazine follower plate,

Figure 5 is a central vertical section through the device, parts in elevation, with the cover opened and the follower plate retracted into the locked position,

Figure 6 is a front elevation of the same, and,

Figure 7 is a horizontal section taken on line 7—7 of Figure 1, parts in elevation.

In the drawings, where for the purpose of illustration, is shown a preferred embodiment of my invention, the numeral 10 designates a cartridge magazine or container, which is rectangular in transverse cross section, open at its lower end, and which has a preferably semi-cylindrical upper closed end 11. The magazine 10 is elongated vertically, and has vertical sides 12 and 13, and generally vertical slightly forwardly inclined front and rear sides 14 and 15. The rear side 15 increases in thickness toward its upper end. The front and rear sides 14 and 15 have upper circular aligned openings 16 and 17, for purposes to be described. The side 13 has a center generally vertical longitudinal guide slot 18, parallel to the inner guide surfaces of the front

and rear sides 14 and 15. The upper end of this slot 18 terminates adjacent to the lower edges of the aligned openings 16 and 17, and the slot extends to the lower end of the side 13, and is open at that end. Arranged diametrically of the circular opening 17, and suitably rigidly secured in the sides 12 and 13, near the upper ends of the same, is a horizontal plunger stop pin 19. The rear side 15 of the magazine 10 carries rearwardly extending hinge knuckles 20, which are adjacent to the lower end of the magazine. The forward side 14 carries a forwardly extending U-shaped latch holder or loop 21, also adjacent to the lower end of the magazine 10. The bottom edge of the forward side 14 has a rectangular recess 22, which is adjacent to the latch holder 21.

Arranged for reciprocation within the aligned openings 16 and 17, and normally supported without 20 in the opening 17 and extending horizontally rearwardly of the magazine 10, is a cylindrical tubular charger or loading plunger 23. This plunger 23 is open at both ends, and has parallel diametrically arranged longitudinal slots 24, extending for substantially the full length of the plunger, but terminating short of the ends of the same. The slots 24 receive the plunger slot pin, and this pin limits the inward and outward movement or reciprocation of the plunger 23. The plunger 23 carries a transverse spring keeper pin 25, near its outer or rear end, and this pin is rigidly secured within openings formed in the plunger. Arranged within the plunger 23, and having its opposite ends in engagement against the pins 19 and 25, is a suitable coil compression plunger spring 26, for maintaining the plunger 23 in its normal rearwardly extended position.

Arranged beneath the magazine 10, and adapted for covering the lower open end of the same, is a magazine cover and main spring housing 27. This cover 27 is rectangular in horizontal cross section, open at its top side, and has a flat rectangular bottom 28. Rigidly secured to the rear of the cover 27, near the upper end of the same, and extending rearwardly of and above the cover, and between the hinge knuckles 20, is a cover hinge knuckle 29, which receives a hinge pin 30, also received by the knuckles 20. One side 31 of the cover 27 has a short generally vertical guide slot 32, which terminates slightly below the open top side of the cover, and leads into a short lateral upwardly inclined locking slot 33. The slot 32 registers with and forms a part of the slot

18, when the magazine cover 27 is closed, see Fig. 1.

Rigidly secured to the forward end of the cover 27, near the bottom of the cover, are forwardly extending knuckles 34 which receive a pivot pin 35. Pivotaly mounted upon the pivot pin 35, and arranged between the knuckles 34, is a vertical latch 36. The latch extends upwardly beyond the knuckles 34 and has a latch head 37, having a latch recess 38, within which the latch holder or loop 21 engages, to fasten the magazine cover 27 in the closed latched position. The latch 36 has a lower depending portion 39, having a stop lug 40 for engaging against the cover 27, to limit the vertical swinging movement of the latch when the cover 27 is opened as in Figure 5 of the drawings. A suitable light coil compression latch spring 41 is arranged in a recess 42, formed in the forward end of the cover 27, and this spring maintains the latch 36 in the locked or latched position, shown in Figure 1. A recess 43 is provided in the forward end of the cover 27, near the open top side of the cover, and this recess registers with and forms a part of the recess 22, when the magazine cover 27 is closed. The recesses 22 and 43 provide the necessary clearance for swinging the latch 36 inwardly, to unlatch and open the magazine cover 27.

Arranged within the magazine cover 27, and also within the magazine 10, when the cover is in the closed position, see Figure 1, is a main or follower plate spring 44, which is a compression spring, having elongated generally oval-shaped coils. When the cover 27 is closed, one end of this spring 44 engages against the flat bottom 28 of the cover, and the opposite upper end coil of the spring engages against the lower flat surface of the follower plate and is secured thereto by a depending lug 45, carried by a horizontal transversely circularly curved follower plate 46. The follower plate 46 is adapted for supporting suitable cartridges or bullets 47 and has a centrally located depending lug or boss 48, having a transverse extension or pin 49, for engaging and sliding within the slots 18, 32, and 33. A button or knob 50 is rigidly secured to the outer end of the extension 49, and is arranged exteriorly of the magazine 10. This button 50 is used to move the follower plate 46 against the force of the main spring 44.

In Figure 1, the numeral 51 designates a revolver cylinder, or the like, and shows the same in position for being loaded with cartridges by this device.

The operation of the device is as follows:

The button or knob 50 is pushed downwardly, moving the pin 49 downwardly in the slot 48, and into the slot 32. The button 50 is then pushed laterally to move the pin 49 into the inclined locking slot 33, where the pin will be held locked under the force of the compressed main spring 44. When this is done, the main spring 44, follower plate 46, and associated elements are all substantially held inclosed with the cover 27. The device is then inverted, as shown in Figure 5, and the cover 27 is unlatched, and swung into the opened position, with the main spring, follower plate, and associated elements. A suitable number of proper size cartridges 47 are next dropped into the magazine where they become arranged horizontally, one above the other.

When the magazine 10 is filled with cartridges, the cover 27 is swung to the closed position and

is automatically latched closed. The pin 49 is disengaged from within the inclined locking slot 33, and again moved into the slots 32 and 18. The main spring 44 now forces the follower plate 46 upwardly against the lowermost cartridge in the magazine, as viewed in Figure 1. The forward and rear ends of the cartridges 47 are guided upwardly in the magazine 10 by the inner surfaces of the sides 14 and 15.

The uppermost cartridge in the magazine engages the semi-cylindrical end 11, and is held in position by the follower plate, and by the other cartridges below it. The device is now again in the upright position, and is ready for use in loading a revolver, or the like.

When it is desired to inject a cartridge into the revolver cylinder 51, or the like, the plunger 23 is pushed inwardly against the force of the spring 26, by the thumb of the user. This plunger forces the uppermost cartridge 47 through the circular discharge opening 16, and out of the magazine 10. The plunger will return to the normal position, when released, and the follower plate and main spring 44 move the next cartridge upwardly into position for being ejected from the magazine by the plunger 23. The loading process can continue until the magazine is empty.

Obviously, this device can be made in various sizes, for accommodating various caliber cartridges.

It is to be understood that the form of my invention herewith shown and described is to be taken as a preferred example of the same, and that various changes in the shape, size and arrangement of parts may be resorted to, without departing from the spirit of my invention, or the scope of the subjoined claims.

Having thus described my invention, what I claim is:

1. A device for loading a revolver or the like, comprising a magazine having a guide slot, forward and rear aligned openings, and an open end, a loading plunger mounted within the rear opening and adapted for ejecting cartridges through the forward opening, a hinged cover associated with the magazine and adapted for covering the open end of the same and having a short guide slot and a locking slot, the arrangement being such that when the hinged cover is closed the short guide slot registers with and becomes a part of the first-named guide slot, a follower plate including an extension for engaging within the guide slots and adapted for being locked within the locking slot, and a main spring associated with the follower plate and arranged within the magazine and within the cover and adapted for causing the follower plate to move cartridges into position for being injected into a revolver cylinder or the like.

2. A device for loading a revolver or the like, comprising a magazine having a guide slot and an open end and provided with cartridge discharge means, ejecting means to discharge cartridges through said discharge means, a hinged cover secured to the magazine and adapted to cover the open end of the same and having a short guide slot and a locking slot, the arrangement being such that when the hinged cover is closed the short guide slot registers with and becomes a part of the first-named guide slot, a follower plate including an extension for engaging within the guide slots and adapted for being locked within the locking slot, and a main spring associated with the follower plate and arranged

5

within the magazine and within the cover and adapted for causing the follower plate to move cartridges into position for being injected into a revolver cylinder or the like.
